(57) **CLAIM**

The ornamental design for a clipper box, as shown and described.

DESCRIPTION

FIG. 1 is a front perspective view of a clipper box, showing my new design;

FIG. 2 is a front side plan view thereof;

FIG. 3 is a rear side plan view thereof;

FIG. 4 is a right side plan view thereof;

FIG. 5 is a left side plan view thereof;

FIG. 6 is a top plan view thereof;

FIG. 7 is a bottom plan view thereof; and,

FIG. 8 is a front perspective view thereof, where the box is open.

The broken line showing of the clippers in FIG. 8 is included for the purpose of illustrating environment and forms no part of the claimed design.

1 Claim, 8 Drawing Sheets

FIG. 2

FIG. 3

FIG. 4

FIG. 5

FIG. 6

FIG. 7
